[57] CLAIM

The ornamental design for a cantilever for a toy building set, as shown and described.

DESCRIPTION

FIG. 1 is a top perspective view of a cantilever for a toy building set showing my new design;
FIG. 2 is a front elevational view thereof;
FIG. 3 is a right side elevational view thereof, the left-side elevational view being a mirror image thereof;
FIG. 4 is a rear side elevational view thereof;
FIG. 5 is a top plan view thereof; and,
FIG. 6 is a bottom plan view thereof.

FIG. 6

FIG. 4

FIG. 3

FIG. 2

FIG. 5

FIG. 1
